UNITED STATES PATENT OFFICE.

CHARLES S. PRICE, OF BETHLEHEM, PENNSYLVANIA, ASSIGNOR TO L. F. GRAMMES & SONS, INC., A CORPORATION OF MARYLAND.

PROCESS OF MAKING BOXES.

Application filed February 5, 1928. Serial No. 88,254.

My invention relates to processes for making boxes, such as cigar boxes and the like, and the object of the invention is to provide an improved process which is simpler and more efficient than the process usually employed in the manufacture of boxes and which effects substantial economies in the time and labor involved.

The process usually employed in the manufacture of such boxes is as follows, first to nail a side and end of the box together with a right-angle joint to form one corner of the box; then to do likewise with the other side and end of the box; next to assemble the two right-angle parts, thus made, into rectangular form and nail them together at one free or unsecured corner; then to nail the same together at the remaining free or unsecured corner to complete the rectangular frame of the box; and thereafter to apply the bottom of the box to the frame in inverted position and to nail it simultaneously to one side and one end of the box; and lastly to nail the bottom simultaneously to the other side and end of the box to complete its construction.

This customary process not only involves many steps, but is cumbersome and unsatisfactory on account of the separate handling of the parts and of the various sub-assemblies thereof, before all of the parts of the box are finally brought together and secured in assembled relation.

By means of the present invention, the handling of the parts is reduced to a minimum, the various sub-assemblies are obviated, and the separate parts composing the box are all secured together in the first step of the process in preliminarily assembled form, and may be conveniently handled as a unit in that form until and during the final assembly and completion of the box.

Another object of the invention is simultaneously to nail the bottom to the sides and ends of the box while these parts are entirely separate from each other and are held in the positions which they occupy in the finished box, so as thereby to form a preliminary assembly in which the sides and ends are separately secured to the bottom but are free from each other, then to withdraw such preliminary assembly as a unit from the holding means, and thereafter to nail together the

meeting edges of the sides and ends to fasten the corners of the box, secure it in permanently assembled relation and thus complete its construction.

With these and other objects in view, the invention comprises all the various novel features hereinafter described and illustrated in the accompanying drawing, in which—

Fig. 1 is a perspective view showing in juxtaposition the separate parts entering into the construction of the box.

Fig. 2 is a perspective view illustrating the first step of the process in which the bottom is nailed simultaneously to each of the sides and ends.

Fig. 3 is a similar view illustrating the next step in which two of the free or unsecured corners of the box are nailed together.

Fig. 4 is a similar view illustrating the final step in which the remaining free or unsecured corners of the box are nailed together and the completed box produced.

Similar numerals refer to similar parts throughout the several views.

According to my invention the process of making a box from its separate component parts, such as a bottom 1, two sides 2 and 3, and two ends 4 and 5, is as follows:

The bottom 1 is nailed as indicated at 6 simultaneously to each of the sides 2 and 3 and ends 4 and 5, while these various parts are separate from each other and are held in the positions which they occupy in the completed box and in which the bottom extends across and abuts against the adjacent edges of the sides and ends.

The relative positions of the parts may, of course, vary somewhat according to the form of the box desired. The ends 4 and 5 preferably extend across and overlap the extremities of the sides 2 and 3 for a purpose hereinafter pointed out; although such an arrangement is not essential. As shown the sides are inset from the ends at their edges remote from the bottom, as is usual, for instance, in cigar boxes; but this is also unnecessary.

The bottom, sides and ends may be held in their respective positions by being fitted to a form, engaged by gages, or in any other suitable manner.

The simultaneous nailing of the bottom to each of the sides and ends may be accom-

plished by any appropriate nailing mechanism, as will be apparent to those skilled in the art. As the bottom extends across and abuts against the adjacent edges of the sides 5 and ends, the nails are driven through the overlapping portions of the bottom and into the respective sides and ends, in the same direction, whereby to simplify this step and permit the simultaneous driving of the nails to 10 be conveniently accomplished.

In Fig. 2 of the drawing two nails 6 are shown as driven through the bottom into each side and one nail 6 into each end, but it will be understood that this is merely for the purpose of illustration and that the number of 15 nails may be varied to suit the size and purpose of the box, provided there is at least one nail so driven into each side and end.

As a result of this first operation or step 20 in the process, the sides and ends are each separately secured to the bottom, although left free from each other, and a preliminary assembly is produced in which all of the parts are held together in substantially the positions which they occupy in the finished box. Notwithstanding the fact that the sides and 25 ends are separate from each other and the corners of the box free, the nails 6 hold the parts in association and permit the preliminary assembly to be handled as a unit until and during the completion of the box. The preliminary assembly may thus be withdrawn from the form or gages or other holding means and will still retain substantially the 30 shape of the finished box.

It is to be noted that in this preliminary assembly the sides and ends, being free from each other, will yield sufficiently relatively one to the other to permit their being tried up, as may be necessary in the subsequent part 40 of the process to insure obtaining a perfect product.

To complete the box, the corners thereof are fastened by nailing together the meeting 45 extremities of the sides and ends. This may be accomplished in two steps, as illustrated in Figures 3 and 4, respectively.

Referring to the step illustrated in Figure 3, both corners of the box adjacent the end 50 4 thereof are simultaneously nailed, as indicated at 7. As each end of the box extends across and overlaps the adjacent extremities of the sides, as above pointed out, the nails 7 at these two corners are driven through 55 the overlapping portions of the end 4 and into the respective sides 2 and 3. By virtue of this arrangement, the nails 7 are all driven in the same direction and hence may be conveniently driven simultaneously at both of 60 these corners of the box. The simultaneous driving of the nails may be effected by any suitable nailing mechanism, as will be apparent to those skilled in the art. The number of nails 7 driven at each corner will, of 65 course, depend upon the size and require-

ments of the box, although in the present instance three are shown for the sake of illustration.

The next step is to fasten the remaining unsecured or free corners of the box, that is 70 the corners adjacent the end 5, by means of nails 8, which are simultaneously driven in both corners similarly to the step last described, whereby to complete the permanent assembly of the parts and to produce the 75 finished box illustrated in Figure 4.

It is to be understood that instead of the last two steps above mentioned the box may, if desired, be completed from the preliminary assembly in one step in which the various nails 7 and 8 are simultaneously driven 80 at all four corners.

The withdrawing of the preliminary assembly from its holding means, and its capacity for being handled independently 85 thereof, as a unit, pending, and during, the final completion of the box, are of importance, since they permit a ready separation of the nailing in forming the preliminary assembly and the nailing in securing the corners of the box, and hence enable these operations to be performed using separate nailing machines or other equipment, specially adapted or set for the respective steps. Moreover, convenient transfer may be made 90 from the machine employed in the first step to the machine or machines employed in the subsequent step or steps without the necessity of the holding means, which is a part of the first machine, being transferred with the 100 preliminary assembly to such subsequent machine or machines. With the present invention there is, therefore, greater economy and efficiency, a more rapid flow of work, and an increased output.

The insetting of the sides from the ends of the box, as above referred to, is to accommodate a lid or cover, but the invention is not limited to the making of boxes of that form, or to boxes having covers, nor does it relate 110 to applying the covers where the same may be used.

Furthermore, while the invention has been shown and described in connection with a rectangular box having two sides and two ends, 115 it may obviously be employed in producing boxes of other forms.

Various changes may be made in the steps of the process within the scope of the invention, as defined in the appended claims.

Having thus described my invention, I claim and desire to protect by Letters Patent of the United States:

1. The process of making boxes which consists in nailing the bottom to the sides and ends while such parts are separate from each other and held in the positions which they occupy in the finished box, and thereby forming a preliminary assembly, and withdrawing 125 such preliminary assembly from the 130

holding means, whereby to permit such assembly to be handled as a unit and shifted to convenient position for further operation without necessitating the shifting of such holding means.

2. The process of making boxes which consists in nailing the bottom to the sides and ends while such parts are separate from each other and held in the positions which they 10 occupy in the finished box, and thereby form-

ing a preliminary assembly, withdrawing such preliminary assembly from the holding means, as a unit and shifting it to convenient position for further operation without shifting of the holding means, and subsequently 15 securing together the meeting extremities of the sides and ends to complete the box.

In testimony whereof, I have signed my name to this specification.

CHARLES S. PRICE.
